UNITED STATES PATENT OFFICE

CLYDE P. ROSS, OF CHICAGO, ILLINOIS

COMBINED COAL AND CINDER HANDLING PLANT

Application filed January 8, 1927. Serial No. 159,833.

My invention relates to a combined coal and cinder plant and has for its purpose to provide such a plant in which coal for re-coaling locomotives may be received, stored and delivered and in which cinders may be received from locomotives and may be transported to cinder receiving and removing cars. One object is the provision of a plant of the type described which shall be compact and easily operated and which shall involve a minimum of excavation and construction. Another object is the provision of a plant which shall be particularly flexible and quickly operated. Other objects will appear from time to time in the course of the specification and claims.

I illustrate my invention more or less diagrammatically in the accompanying drawings, wherein—

Figure 1 is a transverse vertical section;

Figure 2 is an enlarged detail of the structure shown in Figure 1;

Figure 3 is a front elevation of Figure 2; and

Figure 4 is a detail.

Like parts are indicated by like symbols throughout the specification and drawings.

A indicates a coal receiving track upon which coal cars can be spotted in order to discharge their contents into the hopper A¹ with any suitable gate or closure A² operated for example by the link A³ and the lever A⁴.

B indicates a track upon which locomotives may be positioned for decindering, the cinders being received for example in the hopper B¹ the bottom of which is controlled by the slotted gate B² with the rollers B³ and the track B⁴. B⁵ is a control lever connected to the gate for example by the link B⁶.

C indicates a track upon which the cinder receiving car C¹ may be spotted and D indicates a track adapted to support the locomotive D¹ for coaling. Positioned above the track D is any suitable material storage structure, herein shown as a typical coal hopper or tower including the supporting members D² the transverse members D³ the inclined braces D⁴, the hopper

or pin D⁵ with the inclined bottom D⁶ and the coal delivery D⁷ pivoted as at D⁸ to the spout D⁹.

E generally indicates a tunnel, herein shown with the inclined bottom E¹ which penetrates beneath the hoppers A¹ and B¹. It is provided with the tracks E² on the bottom E¹ and with a pair of supplemental tracks E³ spaced thereabove. The track E² is upwardly inclined as at E⁴ the inclined portion being herein shown as extending to the top of the hopper D⁵. The supplemental tracks E³ are of the same gauge as the tracks E² and are provided at their junction with the inclined portion E⁴, as shown in Figure 4, with a cut away portion E⁵, the purposes for which will later appear.

G indicates any suitable support or tower which aids in supporting the track structure E⁴. It is herein shown as having a laterally extending arm or wing G¹, associated with which is a track G², of the same gauge as the track E⁴ and continues with it. G³ indicate gusset plates on which the track G² is supported and held against movement in relation to the track E⁴ and the tower G. G⁵ indicates a vertical baffle the wings G⁶ of which serve as gusset plates to connect the outer ends of the member G¹ and the track G². G⁷ indicates a gusset plate connecting the top of the tower G with the top of the member G¹. G⁸ indicates a track section longitudinally movable along the channel E⁶ which constitutes the upward continuation of the track E⁴.

G¹⁰ are slots in the gusset plates G³ and the channels E⁶ through which passes the stud or pin G⁹ whereby the track section G⁸ is moved. G¹¹ indicates a link in connection with said studs G⁹ and pivoted at its opposite end to the crank arm G¹². It will be understood that this actuating mechanism may be duplicated at opposite sides of the mechanism. The crank arm or arms are controlled by a sprocket G¹³ on the shaft G¹⁴, which may be rotated by any suitable means for example the chain G¹⁵.

G²⁰ indicates a supplemental track spaced laterally away from the track sections E⁴

E^6 , the purpose for which will later appear.

The track section E^6 continues to the top of the hopper D^5 and terminates in a laterally projecting generally horizontal 5 track section H . H^1 indicates a track section generally continuing the track E^6 , but separated therefrom by a gap and H^2 is a supplemental laterally spaced track section corresponding to the section G^{20} . H^3 indicates a hinged door normally in position 10 as shown in full line in Figure 1 but adapted to be swung upwardly into the dotted line position there shown.

J is a hoist bucket having a pair of supporting wheels J^1 the bottom of the bucket and an additional pair of supporting wheels J^2 adjacent the top of one side of the bucket. J^3 are supplemental wheels the purpose of which will later be indicated. J^4 is a 15 pivoted bail to which may be secured the hoist cable J^5 . J^6 is an idler adjacent the opening of the tunnel E . J^7 J^8 are sheaves at the top of the hopper D^5 . J^9 is an idler and J^{10} is a hoist drum adapted to be actuated by any suitable mechanism within the 20 tower house J^{10} . Mounted at the end of the bail J^4 are rollers J^{11} the use of which will be described.

It will be realized that whereas I have 25 described and shown a practical and operative device, nevertheless many changes might be made in size, shape, number and disposition of parts without departing from the spirit of my invention. I therefore 30 wish my drawings to be taken as in a broad sense illustrative or diagrammatic rather than as limiting me to my specific showing.

The use and operation of my invention are as follows:

40 In locomotive upkeep it is of course necessary constantly to supply the locomotives used with fresh increments of fuel and constantly to remove from the locomotives the solid waste products of combustion in the 45 form of ashes or cinders. It is important to render it possible to coal and decinder locomotives as rapidly as possible with a minimum track space and a maximum flexibility. It is also important, in order to 50 keep down the cost of installation, that a minimum of excavation be necessary. I have developed a peculiarly compact and efficient and easily and cheaply constructed installation wherein locomotives may be easily and 55 quickly coaled and decindered. I illustrate my plant as including a coal receiving track, a decinder track, a cinder car track and a locomotive coaling track, although I do not wish to be limited rigidly to any such 60 arrangement. The coal discharge and cinder discharge tracks are herein shown as arranged in one pair and the cinder receiving and coal receiving tracks in another. Beneath the former two are hoppers and beneath the hoppers extends a tunnel into 65

which can run a hoist bucket. I provide any suitable means for controlling the flow of material from the hoppers and preferably the hoppers are of such size as to be able to accumulate a quantity of material, so that if necessary but one hoist need be used, the accumulated coal or cinders being held in the hopper until the bucket is spotted therebeneath and being released by the release of the gates employed. When filled the bucket is hoisted, by rotation of the drum J^9 which reels in the cable J^5 . When the bucket is in the tunnel it is supported by the wheels J^1 J^2 the former engaging the track E^6 and the latter the supplemental track H^2 . It will be understood that the wheels J^2 have a wider face than the wheels J^1 and J^3 so that the wheels J^1 and J^3 may pass through the gap E^5 in the track E^6 and the wheels J^2 with their wider face will span the gap E^5 . When the bucket reaches the inclined track E^4 the wheels J^1 and J^2 both engage such track. When the bucket is carrying coal the laterally movable track section G^8 is left in closed position and the bucket travels to the top of the track E^6 above the hopper D^5 . The rollers J^{11} of the bucket bail J^4 engage the gate H^3 and swings it into the open or dotted line position as shown in Figure 1. Since the track E^6 terminates in the laterally extending portion H the wheels J^2 ride along the track H . However the supplemental rollers J^3 engage the track H^2 , thus preventing the wheels J^1 from riding out on the track H . Instead they engage the supplemental track section H^1 , and as the hoisting action continues the bucket is tilted into the position shown in dotted line and at the top of Figure 1. The gate H^3 serves as a baffle and the coal is discharged into the hopper D^5 .

When the bucket contains cinders the operator actuates the crank arm G^{12} , by means of the chain G^{15} to lift the track section G^8 into the position shown in Figure 2, thus breaking the connection between the tracks E^4 and E^6 . When the bucket is hoisted the dumping action takes place exactly as above described. The wheels J^2 ride on the track G^2 , the supplemental wheels J^3 ride on the supplemental track G^{20} , and the wheels J^1 are thus enabled to bridge the gap and to ride upon the track E^6 , the result being that the bucket is tilted into the position shown in Figure 2. The cinders are thereby discharged, the baffle G^5 directing them downwardly into the car C^1 spotted therebeneath.

It will be obvious that I may use any desirable means for automatically or non-automatically controlling the hoisting excursion for the separate functions. The bucket may be made to discharge cinders and coal at alternate trips, or the timing and frequency of the trips may be handled manually. I have not illustrated the details of the con-

trolling mechanism for the hoist, since they form no part of the present invention.

I claim:

1. In a combined coal and cinder plant, a coal car track, a locomotive decinderer track, a coal receiving member beneath the coal car track, a cinder receiving member beneath the decinderer track, a coal receiving track and a cinder receiving track, laterally spaced from the coal car track and the decinderer track, and conveying means adapted to receive a load selectively from the coal car track and from the decinderer track and to deliver the load so received, selectively, above the cinder car track or the coal receiving track, including a hoist bucket, and means for guiding it beneath the two first mentioned tracks and above the last two tracks, said guide means including an inclined portion extending upwardly of and laterally over the said last two tracks, individual bucket discharging stations on the inclined guide means substantially vertically aligned with the respective coal and cinder receiving tracks, and at substantially different elevations thereabove, and selectively operable means for delivering to the hoist bucket a load from the first two tracks and selectively operable means for dumping the hoist bucket above the second two tracks.

2. In a combined coal and cinder plant, a plurality of material discharging tracks, hoppers therebeneath, a plurality of material receiving tracks, a conveying bucket and a track therefor, including a portion aligned beneath said hoppers and an inclined portion of said track extending above and over said material receiving tracks, means for moving said bucket from end to end of said track, bucket discharging stations on said inclined portion of the track in substantially vertical alignment with the material receiving track respectively, and means for discharging said bucket selectively above the individual material receiving tracks.

3. In a combined coal and cinder plant, a plurality of material discharging tracks, hoppers therebeneath, a material receiving bucket and a track therefor, said track extending beneath said hoppers, a plurality of material receiving tracks, said bucket track extending upwardly above and laterally over said material receiving tracks, and separate bucket discharge means, associated with said bucket track, for the individual material receiving tracks, said bucket discharging means being substantially vertically aligned with the material receiving tracks and at different elevations thereabove.

4. In a combined coal and cinder plant, a plurality of material discharging tracks, hoppers therebeneath, a material receiving bucket and a track therefor, said track ex-

tending beneath said hoppers, a plurality of material receiving tracks, said bucket track extending upwardly above and overlying said material receiving tracks, and separate bucket discharge means at different elevations, associated with said bucket track, for the individual material receiving tracks, the bucket discharge means for one of said tracks being adapted to discharge directly to a car upon said track and a material storage member positioned above another of said material receiving tracks and adapted to receive material discharged from said bucket at a greater elevation.

5. In a combined coal and cinder plant, a material discharging track, a hopper therebeneath, a material receiving bucket and a track therefor, said track extending beneath said hopper, a plurality of material receiving tracks, said bucket track inclining upwardly above and laterally over said receiving tracks, separate bucket discharge means, associated with said bucket track, for the individual material receiving tracks, said bucket discharging means being substantially vertically aligned with the material receiving tracks and disposed at different elevations thereabove, and a material storage member interposed beneath the highest of said discharge means and the receiving track associated therewith.

6. The combination with a locomotive cinder and coaling plant of an upwardly opening coal hopper, a bucket track extending above the hopper opening, a bucket on said track and means for moving it therewith, a bucket dumping mechanism associated with said track adjacent said hopper, a cover for said hopper adjacent said dumping mechanism and means for raising the cover in response to movement of said bucket, said last mentioned means including a member engagable by the bucket in advance of the bucket dumping mechanism.

7. The combination with a locomotive cinder and coaling plant of a coal hopper, an upwardly inclined bucket track terminating above the hopper, a bucket on said track and means for moving it therewith, a bucket dumping mechanism associated with said track adjacent said hopper, a cover for said hopper pivoted adjacent said dumping mechanism and including a part engagable by the bucket in advance of the dumping mechanism whereby the cover is raised in response to the upward movement of said bucket prior to dumping.

8. In a combined coal and cinder plant, a bucket body, a plurality of track engaging means upon said bucket, a material conveying track along which said bucket is adapted to ride and means for moving the bucket therewith, a gap in said track and a dump track laterally extending therefrom, a fixed supplemental track laterally spaced from

said conveying track adjacent said gap, and supplemental guide means carried by the bucket and adapted to engage the supplemental track to guide one of said track engaging means upon said bucket over said track gap at the time that another of said track engaging means passes through said gap and rides out upon the dump track.

9. In a combined coal and cinder plant, a bucket body, a main track along which said bucket is adapted to ride and means for conveying it therealong, a dump track extending laterally from said track the main track being provided with a gap adjacent to the dump track to give access thereto, a movable track section in the main track adjacent to said gap, and means for moving it to open or close said gap, and a fixed supplemental track, generally parallel with the main track but laterally spaced therefrom, adjacent said gap.

10. In a combined coal and cinder plant, a bucket body, a main track along which said bucket is adapted to ride and means for conveying it therealong, a dump track extending laterally from said track, a movable track section in the main track, and means for moving it to open access to said dump track, a pair of wheels upon said bucket, adapted to engage said main track and dump track as the bucket advances along said track, an additional pair of wheels upon said bucket adapted to engage said main track and means for carrying them across the gap opened by the movable track section, including a fixed supplemental track adjacent the gap and a member upon said bucket adapted to engage said supplemental track.

11. In a combined coal and cinder plant, a bucket body, a main track along which said bucket is adapted to ride, and means for moving the bucket therealong, a dump track extending laterally from said main track, a track section generally aligned with the main track and longitudinally spaced therefrom, the dump track communicating with the main track at the gap between the main track and the track section longitudinally aligned therewith, and a fixed supplemental track, generally parallel with the main track and laterally spaced therefrom bridging the gap in the main track.

12. In a combined coal and cinder plant, a bucket body, a main track along which said bucket is adapted to ride, and means for moving the bucket therealong, a dump track extending laterally from said main material conveying track, a track section generally aligned with the main track and longitudinally spaced therefrom, the dump track communicating with the main track at the gap existing between the main track and the track section longitudinally aligned therewith, and a fixed supplemental track,

generally parallel with the main track and laterally spaced therefrom, said laterally spaced supplemental track being laterally aligned with the gap between the main track and the track section longitudinally spaced therefrom in bridging relation to said gap.

Signed at Chicago, county of Cook, and State of Illinois, this 24th day of December, 1926.
